UNITED STATES PATENT OFFICE.

ABROM B. GIFFORD AND EDWARD E. HULL, OF JESSUP, IOWA.

APPARATUS FOR RAISING TOWERS.

SPECIFICATION forming part of Letters Patent No. 659,607, dated October 9, 1900.

Application filed March 13, 1900. Serial No. 8,504. (No model.)

To all whom it may concern:

Be it known that we, ABRON B. GIFFORD and EDWARD E. HULL, citizens of the United States, residing at Jessup, in the county of Buchanan and State of Iowa, have invented a new and useful Improvement in Apparatus for Raising Towers for Windmills, &c., of which the following is a specification.

One object of this invention is to provide a device of simple, strong, and durable construction which may be readily and quickly clamped to two of the uprights of a windmill-tower and to two of the anchor-posts of a windmill-tower to serve as a pivot upon which the tower may be raised and when the tower is raised to hold the uprights and anchor-posts in proper relative position for receiving bolts through the coinciding openings in the uprights and anchor-posts.

Another object is to provide means whereby the uprights to which the apparatus is applied cannot buckle.

A further object is to provide an apparatus of this class which may be easily and quickly adapted for use in connection with windmill-towers having either three or four uprights.

Our invention consists in certain details in the construction, arrangement, and combination of the various parts of the apparatus whereby the objects contemplated are attained, as hereinafter more fully set forth, pointed out in our claims, and illustrated in the accompanying drawings, in which—

Figure 1 shows the lower end portion of a windmill-tower lying flat upon the ground-surface and an anchor-post set in position and our improved apparatus applied thereto ready for practical use. Fig. 2 shows in detail a side elevation of an anchor-post in the ground, a short section of a windmill-upright, and our device applied thereto as in practical use. Fig. 3 shows a detail perspective view of the part of the apparatus designed to be clamped to an anchor-post. Fig. 4 shows a perspective view of the part of the apparatus designed to be clamped to the tower-upright.

Referring to the accompanying drawings, we have used the reference-numeral 10 to indicate the anchor-post, preferably made of angle-iron in the ordinary manner and hav-

ing the openings 11 at its top portion to receive the bolts.

The reference-numeral 12 indicates a windmill-tower upright, also made of angle-iron and having openings 13 arranged to coincide with the openings 11, so that after the tower is in position the bolts may be passed through the openings 11 and 13 to firmly fasten the tower to the anchor-posts.

It is to be understood in the following description that there are two mating devices designed to be secured to the two lower uprights of a tower and to two of the anchor-posts. These devices are identical in construction and function, and hence but one will be hereinafter fully described. The part designed for attachment to the anchor-post is preferably formed complete in one piece and comprises the sides 14 and 15, extending at right angles to each other. The outer end of each part is slotted at 16, and a bolt 17 is passed through the slot. This bolt 17 has an elongated head 18, and a nut 19 is placed on the outer end of the bolt. At the corner of these parts 14 and 15 are two integral lugs 20, provided with openings 21 to receive the bolt 22 and to form part of a hinge-joint. In use it is obvious that this part just described may be readily and quickly clamped to an anchor-post of any ordinary size by first placing it against the anchor-post, then moving the bolts 17 until the heads 18 overlap the sides of the anchor-post, and finally drawing the nuts 19 tight.

The remaining part of the device comprises a straight bar 23, having an opening at one end, through which the bolt 22 is passed. The width of this bar is preferably slightly less than the space between the lugs 20. Hence a limited lateral movement is permitted in the hinge-joint formed by these parts, the purpose of which will be hereinafter made clear. A slight distance from this bolt 22 a clamping device is fixed to the part 23 by means of a bolt 24. This clamping device is preferably composed of two parts 25 and 25^a, each having a longitudinal slot 26 near its outer end, and the lugs 27 are provided for overlapping the bar 23. The said bolt 24 is passed through these lugs and through the bar 23. Bolts 28, having elongated heads of the same kind as

the heads 18, before described, are passed through these slots 26. At the opposite end of the bar 23 is a clamping device similar to the one just described, but having only one 5 lug 27, and at a point near the lower clamping device is a guide 29, formed on or fixed to the bar 23 and designed to engage the sides of an angle-bar or tower-upright secured in said clamping device to prevent the said upright 10 from curving or bending between these clamping devices. It is obvious that the lower clamping device may be dispensed with when desired without changing the purpose or operation of our invention.

15 To adapt the apparatus for use in connection with windmill-towers having only three uprights, we have provided the wedge-shaped blocks 30, having longitudinal slots therein and designed to have the bolts 28 passed 20 through the slots in the parts 30 as well as the slots in the parts 25. Hence the device may be fitted to the angle-irons of different angles.

In practical use the anchor-posts are first 25 set and the windmill-tower is moved adjacent to the two posts, then the top edges of the parts 14 and 15 of the clamping device are placed a distance below the lower one of the bolt-holes 11 corresponding to the distance from the bottom of the upright 12 to 30 the lower one of the holes 13, and the said parts are then secured to the anchor-post by means of the nuts 19. Then the clamps 25 are secured to the lower part of uprights 12 in such a position that the lower edge of the 35 upright 12 will rest upon the top of the parts 14 and 15 when the uprights 12 are in their elevated position. It is obvious that the guides 29 will then engage the sides of the upright 12. After this is done the tower is 40 elevated in the ordinary way. However, it is obvious that the guy-ropes usually employed to prevent the tower from swinging laterally are unnecessary, and hence may be dispensed with, it being only necessary to 45 apply such power to the tower as will tend to raise it. Then when the tower is raised the lower ends of the uprights will rest upon the top edges of the clamps on the anchor-posts, and the openings in the tower-uprights 50 and anchor-posts will coincide, so that these parts may be firmly bolted together. By permitting a slight lateral play in the hinge-joint it is obvious that the uprights 12 may

readily adapt themselves to accurately fit upon the anchor-posts, and slight lateral 55 strains upon the windmill-tower while being elevated will not interfere with the raising of the tower and will not cause the hinge-joint to bind. The said guides 29 prevent the uprights 12 from bending between the 60 clamps, and hence serve to draw the lower ends of the upright to accurately fit upon the top portions of the anchor-posts.

Having thus described our invention, what we claim, and desire to secure by Letters Patent of the United States therefor, is—

1. An apparatus for raising windmill-towers, comprising in combination, a frame designed to be placed on an anchor-post, means for detachably clamping said frame to the 70 post, a bar hinged to the said frame, and means connected with the bar for detachably securing the bar to a windmill-tower upright, substantially as, and for the purposes stated.

2. An apparatus for raising windmill-towers, comprising in combination, a frame designed to be placed on an anchor-post, a bar hinged to the said frame, a clamp near the upper end of the bar, designed for detachable connection with the windmill-tower upright, 80 substantially as, and for the purposes stated.

3. An apparatus for raising windmill-towers, comprising in combination, a frame composed of the parts 14 and 15 at right angles to each other, and having longitudinal slots 85 near their outer ends, bolts having elongated heads, passed through said slots, perforated lugs at the corner of said frame, a bar 23 designed to enter between said perforated lugs and capable of slight lateral movement therein, a bolt for securing said bar to the lugs, two frames 25 and 25^a connected with the bar 23, and having longitudinal slots in their ends, bolts having elongated heads mounted in said slots, and wedge-shaped blocks 30, 95 also having elongated slots, designed to lie parallel with the sides of the frames 25, and to have said bolts passed through them, and a guide 29 on the bar 23, substantially as, and for the purposes stated.
